UNITED STATES PATENT OFFICE.

THOMAS DWYRE, OF KENDALL, ILLINOIS.

END-GATE.

SPECIFICATION forming part of Letters Patent No. 235,418, dated December 14, 1880.

Application filed October 7, 1880. (No model.)

To all whom it may concern:

Be it known that I, THOMAS DWYRE, of Kendall, in the county of Kendall and State of Illinois, have invented a new and useful 5 Improvement in Drop End-Gates for Wagon-Bodies, of which the following is a specification.

Figure 1 is a perspective view of the improvement. Fig. 2 is a sectional side elevation, showing the end-gate lowered to a horizontal position. Fig. 3 is a plan view of a portion of the improvement, showing the end-gate in a horizontal position. Fig. 4 is a side elevation, showing the end-gate and the ex- 10 tension end-gate in a horizontal position. Fig. 15 5 is a side elevation, partly in section, showing the end-gate and the extension end-gate lowered into a vertical position. Fig. 6 is a sectional top view.

20 Similar letters of reference indicate corresponding parts.

The object of this invention is to furnish drop end-gates for wagon-bodies so constructed that they can be turned down into and sup- 25 ported in horizontal positions to serve as platforms for convenience in shoveling loads from the wagon-bodies, and that they can be swung down into vertical positions, so as to be out of the way.

30 In the accompanying drawings, A represents the bottom boards, B the side-boards, and C the rear end board or gate, of a wagon-body.

D represents the side-boards, and E the 35 rear end board or gate, of an extension or top body. The side-board D can be connected with the side-boards B by stakes or other suitable means.

To the inner side of the end-gate E are attached the upper parts of two metal straps, F, the lower parts of which project downward along the inner side of the end-gate C. The lower parts of the metal straps F have bolts G attached to them, permanently or detachably, which bolts pass through holes in the end-gate C, and have hand-nuts H screwed upon their ends, so as to connect the end-gates E C firmly and detachably.

To the lower end parts of the end-gate C 40 and to the end parts of the rear end of the bottom A are attached eye-straps I, through

the eyes of which passes a rod, J, to hinge the said end-gate C to the said bottom A. The lower side of the rear end of the bottom A and the outer side of the lower end of the end-gate C are beveled to receive the rod J and allow the said edges to come close together when the end-gate C is lowered into a horizontal position, so that a shovel will slide from the end-gate C to the bottom A without catching, and so that the gate C can be swung down into a vertical position.

To the upper rear corners of the side-boards D are pivoted hooks K, to hook upon the projecting ends of a rod, L, passed through the 65 upper parts of cleats attached to the outer side of the ends of the end-gate E, to secure the end-gates E C in place when turned up against the ends of the side-boards D B, and when connected by the straps F and bolts G H. 70 With this construction, by removing the nuts H from the bolts G the end-board C can be turned down, leaving the end-board E in place.

The hooks K are made with double jaws or with slots to receive the rod L, to form square 75 bearings for the head and nut of the rod L when the said nut is screwed up to clamp the said hooks in place.

M are the wings, which are made in the form of quarters of circles, and are formed by attaching sheet-metal plates to malleable-iron frames, or in any other suitable manner. The wings M are pivoted or hinged to the projecting ends of the rod J, and to them, near the rear ends of their curved edges, are pivoted 85 hooks N, to hook upon the projecting ends of the rod O passed through the upper parts of the cleats attached to the outer sides of the ends of the end-gate C. The hooks N are made with double jaws, or with slots to receive 90 the rod O, to form square bearings for the head and nut of the rod O when the said nut is screwed up to clamp the said hooks in place.

When the end-gate C is turned down into a horizontal position the wings M prevent any 95 part of the load that may flow out upon the said gate from falling off at the ends of the gate.

To the inner side of the rear ends of the side-boards B are attached metal straps P, the upper ends of which are bent outward across the upper edge of the side-boards, project outward 100

to overlap the outer sides of the wings M, and serve as guards to keep the said wings in place against the outer sides of the side-boards B. Through the downwardly-projecting upper end 5 of each strap P, and through the side-board B, is passed a rivet, Q, along which the curved edge of the wing M moves, and against which strike projections R formed upon the wing M at the ends of its curved edge, to limit the 10 movement of the said wings. The forward stops R also support the end-gate when turned down into a horizontal position.

To the side-boards B are attached half keepers S, to serve as guides and guards for the 15 curved edges of the wings M when the end-gate C is raised. The half-keepers or guards S are notched or grooved transversely for the passage of a flange, T, formed upon or attached to the side of each wing M near the 20 middle part of its curved edge, and which is perforated to receive a pin, U, to rest against the side of the half-keeper S to hold the end-gate C in place when raised.

Having thus described my invention, I

claim as new and desire to secure by Letters 25 Patent—

1. A drop end-gate for wagon-bodies constructed substantially as herein shown and described, consisting of the end-gate C, the eye-straps and rod I I J for hinging the end-gate 30 to the wagon-body, the quadrantal wings M, having stops R, the hooks and rod N O for connecting the wings and end-gate, the guards P, having rivets Q, to engage with the stops R, and the guards S, flanges T, and pins U for 35 holding the end-gate raised, as set forth.

2. The combination, with the double-jawed hooks K on the side-boards D, of the rod L, adapted both to brace the end-gate E and, by its end extensions, to serve as a catch for the 40 hooks K, as shown and described.

3. The straps P, attached to the inside of boards B, bent out at the upper ends over the edges of said boards, and made to overlap the wings M, as and for the purpose specified.
